UNITED STATES PATENT OFFICE.

MARIUS E. GRISWOLD, OF BURLINGTON, IOWA.

DESIGN FOR A JUVENILE VEHICLE.

51,281.

Specification for Design. Patented Sept. 18, 1917.

Application filed March 14, 1917. Serial No. 154,906. Term of patent 14 years.

To all whom it may concern:

Be it known that I, MARIUS E. GRISWOLD, a citizen of the United States, residing at Burlington, in the county of Des Moines and State of Iowa, have invented a new, original, and ornamental Design for Juvenile Vehicles, of which the following is a specification, reference being had to the accompanying drawing, forming a part thereof.

The figure is a perspective view of a juvenile vehicle showing my design.

I claim:

The ornamental design for a juvenile vehicle, as shown.

In testimony whereof I have signed my name to this specification.

MARIUS E. GRISWOLD.
